UNITED STATES PATENT OFFICE.

LYMAN GUY BARTON, OF WILLSBORO, NEW YORK, ASSIGNOR OF ONE-HALF TO ALBERT A. WHEELOCK, OF ELIZABEHTOWN, NEW YORK.

OBSTETRICAL FORCEPS.

No. 820,845.

Specification of Letters Patent.

Patented May 15, 1906.

Application filed March 30, 1905. Serial No. 252,857.

To all whom it may concern:

Be it known that I, LYMAN GUY BARTON, a citizen of the United States, and a resident of Willsboro, in the county of Essex and State 5 of New York, have invented new and useful Improvements in Obstetrical Forceps, of which the following is a full, clear, and exact description.

My invention relates to obstetrical forceps, 10 and more particularly to those of the axis-traction type.

Its principal objects are to provide such an instrument which may be readily applied to the fetal head and efficiently manipulated to 15 effect delivery.

Reference is to be had to the accompanying drawings, forming a part of this specification, in which similar characters of reference indicate corresponding parts in all the views.

20 Figure 1 is a perspective view of one embodiment of my invention. Fig. 2 is a top plan view thereof. Fig. 3 shows in top plan one of the forcep members separated from its companion. Fig. 4 is a transverse sectional 25 detail on the line 4-4 of Fig. 1. Figs. 5 and 6 are top plan views of the coöperating ends of the blade extensions. Fig. 7 is a sectional detail of the pivotal connection between the members, and Fig. 8 is a similar view of the 30 mounting for the approximating device.

A pair of forcep members are designated by the letters A and B, the former comprising 35 a traction rod or handle portion 10 and a blade portion 11, while the latter has similar elements 12 and 13, respectively. Each handle has a central flattened portion 14, through 40 which is a longitudinal slot 14^a, that of the blade 10 being formed to secure greater lightness of the instrument and being bridged at 15 to support a pivot-pin or projection 16. This pin is rotatable in the bridge, its shank 17 turning in an opening therein and being retained in place by a screw 18, threaded 45 through the side of the portion 14 and entering an annular groove 19 in the shank. The pivot-pin at its outer end is provided with an elongated head 20, the thickness of which is such as to allow it to enter the slot in the 50 companion member and its length being sufficient to hold them against separation when it is turned across the handle. Beyond the 55 portions 14 the handles diverge at 22 to receive the blade portions 11 and 13, which are mounted upon the handles 10 and 12, respec-

tively, for independent rotation. The engaging portions 25 of these blades are preferably formed with the usual contour to adapt them to the head of the fetus and to the pelvic cavity. Extending from the side of each of the blade portions is a pivot-pin or projection 26, which is rotatable in an opening in the end of the section 22 of each handle and may be held against disengagement by a screw entering a groove, as has been described in connection with the main pivot-pin. 65

The blades extend inwardly beyond the pivot-pin at 27, where they are provided with connecting means to allow the coördination of their movements. Upon the extension of the blades 11 are separated walls 28 28, which receive between them a tongue 29, projecting from the extension of the blade 13. Between the walls 28 extends a pivot-pin or projection 30, which may engage a recess 31 in the side of the companion extension. When the pin 70 and recess are in coöperation, they may be locked to prevent separation by a member 32, turning about a screw 33, threaded into the end of the pin 30, and having in its under side a transverse slot or recess 34 to receive a 75 pin or projection 35 from the extension of the blade 13, which seats itself in a depression 36, opening from the outer wall of the recess 34. The member 32 may be knurled or corrugated 80 at 37 to facilitate engagement by the fingers 85 of the operator.

At the ends of the handles opposite the blades are grip portions 38, extending therefrom at a suitable angle, and adjacent to these, upon the upper faces of the handles, 90 are posts 39 and 40, which are rotatably mounted in a manner similar to the pivot-pins and are bifurcated at their outer extremities. Between the fork of the post 39 is hinged a rod 41, which may enter the fork 95 of the post 40 and is threaded to receive a thumb-nut 42.

In use the forcep members are separated and are independently introduced into the uterus until the end of the blade of each 100 touches the head, by which it will be deflected, and by virtue of its pivotal connection with the handle will glide between said head and the pelvic wall and assume the proper position, the handles at all times maintaining 105 substantially an axial position with relation to the pelvis. When both blades have thus been applied, the pin 16 is caused to enter the

groove in the handle of the companion member and its head is turned to secure them. The members may now be moved longitudinally until the recess 34 comes opposite the pin 35, when they may be brought into coöperation and the blade extensions locked by the member 32. The screw 41 is now swung into the bifurcation of the post 40 and its nut turned until the blades are properly approximated. It will be seen that when closed upon the head they may occupy an angular position with relation to the handles, this varying between such limits as are indicated in full and dotted lines in Fig. 2 of the drawings. The instrument is now ready to apply traction to aid in delivery. With the forceps ordinarily employed, the blade and handle being continuous and not moving independently, application to the fetal head in the medium and high positions cannot be made without disturbing its relation to the proper pelvic diameters, in which it is necessary to descend, even though the instrument be rotated on its own axis through a considerable angle and the handles markedly depressed against the perineum. As a consequence greater compression force is required to prevent slipping of the blades and greater traction force is required to complete delivery. This entails increased risk to both fetus and maternal tissues. With my improved forceps, however, by means of the independent action of blades and handles exact application to the head may be made without disturbing its proper relation to the pelvic diameters, the handles remaining in the axis of the interior strait without depression against the perineum. As a consequence the head descends in a proper attitude, less compression and less traction force being required, and as parturition proceeds the handles may be shifted longitudinally upon one another, this causing the blades to rotate together to follow the head, thus permitting the handles to remain in an axial position and the blades to maintain their fixed relation to the head. The capability of independent movement of the blade upon the handle in application and the simultaneous rotation of the blades during traction especially adapts this instrument for such positions of the fetus as when the longitudinal diameter is in the oblique or transverse diameter of the pelvis. It should be noted that while in the ordinary axis-traction forceps it is necessary to provide independent handles and traction - rods in my improved forceps these are furnished by a single pair of members.

Having thus described my invention, I claim as new and desire to secure by Letters Patent—

1. Obstetrical forceps, comprising associated members, each having a handle, and a blade pivoted to the handle, the handle and the blade of one member being pivotally con-

nected to the handle and the blade of the other member.

2. Obstetrical forceps, comprising associated members, each having a handle, and a blade pivoted to the handle, the handle and the blade of one member being pivotally connected to the handle and the blade of the other member, and the handles being movable longitudinally with respect to each other. 70

3. Obstetrical forceps comprising associated members, each having a handle and a blade portion, said members being pivotally connected and also movable longitudinally of one another. 75

4. Obstetrical forceps comprising coöperating handles, blades pivoted upon the handles, and means for simultaneously swinging the blades with respect to the handle through their connections therewith. 80

5. Obstetrical forceps comprising coöperating handles, blades movable upon the handles, said blades being pivotally connected to one another. 85

6. Obstetrical forceps comprising a pair of associated members composed of a blade and a handle pivotally connected, the members being movable longitudinally of each other, and means for constraining the blade portions to move symmetrically. 90

7. Obstetrical forceps comprising a pair of associated members, one of which has a slot and the other a projection operating in the slot and furnishing a pivotal connection. 95

8. Obstetrical forceps comprising a pair of associated members, one of which has a slot and the other a projection operating in the slot, said projection being rotatable upon its member and provided with an elongated head. 100

9. Obstetrical forceps comprising a pair of handles pivoted to one another, and a blade pivoted upon each handle, on an axis perpendicular thereto. 105

10. Obstetrical forceps comprising a pair of handles pivoted to one another, a blade pivoted upon each handle and being extended inwardly beyond their pivots, and a connection between the blade extensions. 110

11. Obstetrical forceps comprising a pair of handles pivoted to one another, a blade pivoted upon each handle and being extended inwardly beyond their pivots, one of said blade extensions being provided with a recess and the other with a coöperating pin, and means for locking the pin within the recess. 115

12. Obstetrical forceps comprising a pair of handles pivoted to one another, a blade pivoted upon each handle and being extended inwardly beyond their pivots, one of said blade extensions being provided with a recess and the other with a coöperating pin, a projection upon one of the extensions, and a member movably mounted upon the other extension for engagement with the projection. 125

130

13. Obstetrical forceps, comprising independently-movable handles, blades pivoted to the handles on an axis perpendicular thereto, means whereby the handles may be moved longitudinally with respect to each other, and means whereby the blades may be constrained to move in definite relation with respect to each other.

In testimony whereof I have signed my name to this specification in the presence of 10 two subscribing witnesses.
